Primary Examiner — Cathy Anne MacCormac(74) *Attorney, Agent, or Firm* — Thomas P. O'Connell; O'Connell Law Firm(57) **CLAIM**

I claim the ornamental design for a home for pets, as shown and described.

DESCRIPTION

FIG. 1 is a perspective view of the home for pets showing the door to the balcony in an open position;

FIG. 2 is a perspective view thereof showing the door to the balcony in a closed position;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom plan view thereof;

FIG. 8 is a perspective view thereof showing the roof pivoted to an open position and the feeding tray opened to an extended position;

FIG. 9 is a cross-section thereof taken along the line 9-9 in FIG. 3;

FIG. 10 is a cross-section thereof taken along the line 10-10 in FIG. 4;

FIG. 11 is a cross-section thereof taken along the line 11-11 in FIG. 5; and,

FIG. 12 is a cross-section thereof taken along the line 12-12 in FIG. 6.

The broken lines depict environmental subject matter and form no part of the claimed design.
